Application December 26, 1950, Serial No. 202,766

1. CH_3Cl (Cl-38-14)

1. INTRODUCTION

卷之三

s to and has for an object. Other

This invention relates to and has for an object the provision of a flexible ironing board cover of fabric which is capable of ready attachment to and detachment from a conventional ironing board and which, when applied for use, will stretch and remain stretched on a board against accidental displacement and is free from usual fasteners, clips, springs or other devices sometimes employed.

It is well known that usual covers for such a purpose consist merely of a sheet of cloth stretched over the top surface and marginally extended over the lateral edges and thence under the board and fastened as by means of pins, clips, or otherwise. Other covers have been applied and held stretched as by means of cords, elastic bands or springs connected to opposite marginal portions of the sheet beneath the board, or occasionally held at the edges of the boards in grooves as by means of tensioned rods or other types of retainers.

All of such devices have been found to be more or less inconvenient, troublesome and otherwise unsatisfactory.

Hence, it is a primary object to provide a cover of maximum durability, convenience and economy and having features designed to expedite and facilitate its attachment to and detachment from a board, together with sufficient flexibility and elasticity to hold the cover taut on a board while sufficiently extensible to be easily attachable and detachable.

To such end a cover embodying this invention includes a single fabric sheet of a width greater than the board to which it is applicable, so as to be marginally extended over the lateral edges and thence under the board, while the fabric is so cut at the foot on biased lines from each lateral margin to provide overlapping folds and an included pocket for receiving the foot of a board.

The head portion of the cover has a transverse section of elastic fabric secured to the adjacent head of the cover sheet on a transverse line at the head edge and thence extended downwardly over said head edge and under the bottom surface of the board. Also lateral narrow sections of elastic fabric extend over the lateral edges of the board for short distances and underlie the board. Thus a head pocket is formed between the cover sheet and said elastic sections which is self adapting to the contour of the board in the vicinity of the head and serves to stretch the cover over the top of the board.

38-140) 2
Other objects may appear as the description progresses.

An embodiment of the invention is shown in the accompanying drawing in which:

Figs. 2, 3 and 4 are cross sectional views of the same on lines 2-2, 3-3 and 4-4 of Fig. 1.

Fig. 5 is a perspective view of the cover detached.

The cover, as at C, is fitted over a pad P onto board B and is formed with an elongated cover section 1 of fabric with laterally opposite and similar edge portions 2, 2 adapted to extend downwardly over the lateral edges of board B and thence inwardly under the board as at 3, 3, near a location corresponding to that of the foot of the board. The marginal portions 3, 3 are cut diagonally at 4, 4 so as to provide overlapping sections 5, 5 which form a pocket between the cover section 1 and the sections 5, 5 adapted to receive the foot of board B. The end 6 of said pocket conforms in contour to the end of the board and closes said pocket.

The head portion of cover C is formed of a section 7 of elastic fabric extended transversely across and sewed to section 1 and is sewed to an end portion 8 over the head edge of the board on a line 9. Similar sections of elastic fabric 10, 10 are extended along the lateral margins of the cover from an edge 11 of section 7 toward the foot of the cover for correspondingly short distances and are sewed to edge 11 of section 7 and at points 12, 12 to the edge portions 3, 3. Thus, the sections 7 and 10, 10 form a pocket under cover section 1 for receiving the head of board B. Pad P may be secured to section 1 or separate therefrom.

Cover C is attached to the board B by holding the cover at a point toward the head section and pulling the cover with section 1 uppermost over the upper surface of the board until the foot of the board seats in the pocket formed by sections 5, 5, and then stretching the cover to an extent which will position section 7 so that it will slip under the board and the head of the board will seat in the pocket formed by sections 1 and 1. Release of section 7 will allow the attachment of the head portion to the board due to the elasticity of section 7. Also the marginal elastic sections 10, 10 will be simultaneously drawn under the lateral margins of the board in like manner.

Obviously, when the cover is attached in the manner shown and described it will remain tautly stretched over board B against unintentional displacement, but may be readily detached by

elongating the cover so as to pull the head pocket off of one end of the board, after which when the cover is pulled in a reverse direction the foot pocket will be detached.

The peculiar form of the sections 5, 5 forming the foot pocket serves to provide ample tension in the non-elastic material of the cover to neatly pull the marginal portions 2 and 3 over the edges of and under the board B by reason of the transverse tension and stretch of the material while the elasticity of the sections 7 and 10, 10 at the head of the board supplements the transverse stretch and provides ample longitudinal stretch and tension to assure a smooth ironing surface and retention of the cover on the board.

We claim:

A cover for ironing boards comprising: a section of fabric adapted to overlie the top and edges of an ironing board and formed at one end on each side thereof with angular extensions presenting overlapping sections with inner margins thereof disposed diagonally and providing a pocket to receive the foot of said board, said overlapping portions being permanently sewed together, and a transverse section of elastic

tic fabric extended transversely in the plane of said overlapping sections at the other end of the cover and secured to end marginal portions of said cover section, said transverse elastic section

5 forming a pocket to receive the head of said board, and short marginal sections of elastic fabric extending along marginal continuations of the overlapping sections of said fabric cover, each secured at one end to the corresponding 10 marginal continuation of one of said overlapping sections and at its other end to the transverse elastic fabric section.
